UNITED STATES PATENT OFFICE

THOMAS GARE, OF STOCKPORT, ENGLAND

WEARING SURFACE OF PAVEMENTS, ROADS, TREADS, AND THE LIKE

Application filed June 25, 1928, Serial No. 288,209, and in Great Britain August 19, 1927.

This invention relates to that kind of wearing surface of pavements, roads, treads and the like which is composed of pieces of rubber and a mass of solid cement, the pieces of 5 rubber being laid in the upper part of the mass during the production of the said mass, so as to have their upper surfaces exposed and leave exposed upper areas of the cement mass, and preferably projecting slightly above the 10 top surface of the cement mass.

The object of the said invention is to prevent in a comparatively uncostly manner, the said pieces from lifting or being pushed, kicked or picked out of the cement whilst also 15 avoiding the presence in the cement of weak areas or parts liable to crumble or be broken away.

I attain these objects and advantages by the means illustrated in the accompanying sheet 20 of drawings, in which

Figure 1 is a fragmentary plan view of a wearing surface and illustrates one construction.

Figure 2 is a view in section on line 2—2 of 25 Figure 1.

Figure 3 is a view in section on line 3—3 of Figure 1.

Figure 4 is a fragmentary plan view of a wearing surface and illustrates a second construction.

Figure 5 is a fragmentary plan view of a modified detail.

Figure 6 is a fragmentary plan view of a wearing surface and illustrates a third construction.

Figure 7 is a fragmentary plan view of a wearing surface and illustrates a fourth construction.

Figures 8 to 11 show some different cross- 40 sections of rubber which may be utilized.

Figure 12 shows a detached end view in section and illustrates a modification.

Referring to the drawings, in the construction shown in Figures 1 to 3, a plurality of 45 oblong blocks 1 of soft rubber, of flat-oblong cross-section are secured together by rods or wires 4 which extend laterally through the blocks 1 at their ends and link the blocks 1 together in the manner of a multiple-link chain. The wires 4 are situated near the ends

of the blocks 1 and the ends are connected together in an alternate manner and abut laterally against each other with the result that oblong apertures completely surrounded by rubber blocks are present in the fabric formed 55 by the connecting together of the rubber blocks.

Wires or rods 5 are also provided to extend through the blocks 1 and along the centres of the said apertures in a longitudinal direction 60 relative to the blocks 1 and said apertures.

This fabric of connected rubber blocks 1 is placed on a bed 6 of cement, see particularly Figures 2 and 3, which is laid where the pavement or the like is required and is pressed 65 onto the bed 6. The cement oozes up into the apertures and partly fills them. A mixing or preparation of the cement is then placed on the fabric and worked into the apertures to complete the filling thereof to the desired extent, see Figures 1 and 3. The surplus is then removed by brushing or other suitable means. The cement is then allowed to set or harden.

The finished pavement thus consists of islands 7 of cement surrounded by rubber in 75 the form of oblong blocks 1 the upper surfaces of which project slightly above the surfaces of the islands 7 which are integral with the mass forming the bed 6. The rods or wires 4 and 5 secure the blocks firmly against lifting and the said islands prevent material movement of the blocks in a lateral or longitudinal direction. The localized contraction and expansion of the comparatively small, separate blocks 4 of rubber is so slight as 80 not to cause them to become materially loose and the small strains due to such expansion and contraction are amply resisted by the wires 4 and 5 and islands 7. Furthermore the action of moisture or water which may get 85 between the rubber and the bed 6 is localized and even although the rubber blocks 1 may not adhere to the cement, they are securely retained in position by the rods or wires 4 and 5 and the material 7 which is integral with the 90 bed 6 and fills the apertures in the fabric of connected rubber blocks 1.

The rubber blocks 1 are sufficiently close together to ensure that the foot of a person walking on the pavement comes to rest on the 100

rubber blocks, and under dry conditions, when a cement surface is liable to cause slips, act to prevent such slips, but under wet or greasy conditions when a cement surface is less liable to cause slips, the presence of the islands 7 of cement or the like counteract any tendency of the wet or greasy rubber blocks to cause slipping.

It will be appreciated that the rubber blocks 10 may also be arranged so as not to abut against each other at the sides. A construction of this kind is shown in Figure 4, the rubber blocks 8 being in displaced arrangement and having cross wires 9 and longitudinal wires 15 threaded through them to connect them together and secure them in the bed 11 of cement. In this arrangement the harder material or substance 11 completely surrounds each rubber block 8. To retain the blocks 8 in spaced relationship on the wires 9 before they are bedded in the cement any suitable distance pieces may be threaded on the wires 9. For example a spring 12, Figure 5, may be provided on the wires 9 between each two adjacent blocks 8.

It is to be understood that the rubber blocks may be disposed or spaced in many other ways and that the connecting and/or anchoring wires or rods may also be disposed or threaded 30 through the blocks in many other ways.

Figures 6 and 7 illustrate by way of example two other arrangements.

In Figure 6 displaced rubber blocks 13 are connected together by cross wires 14 and longitudinal wires 15 to produce apertures which are filled with cement or the like 16, small rubber blocks 17 being provided on the wires 14 between some of the ends of the rubber blocks 13 to act as distance pieces and also maintain a continuity of the rubber blocks whilst at the same time obtaining larger apertures for the reception of the cement 16.

In Figure 7 displaced rubber blocks 18 are provided and are connected together by cross wires 19, long blocks or lengths 20 of rubber being provided between the ends of the blocks 18 and threaded on the wires 19. Longitudinal wires 21 extending through the long blocks or lengths 20 are also provided and cross the wires 19. This arrangement produces displaced apertures filled with cement 22.

It will be observed that in all of the hereinbefore described constructions or arrangements some or all of the wires are embedded 55 at different parts of lengths in the cement or the like.

The rubber blocks or lengths, bed and fillings of the interstices or apertures may be produced in the form of slabs or flags for laying to form pavements or for use as stair or step treads and so forth. To produce slabs or flags a mould is preferably employed and the fabric of rubber and wire or rods is placed 60 in the bottom of the mould which is then

filled with the cement. The cement enters the interstices or apertures to fill them and also fills that part of the mould which is not occupied by the said fabric. When the cement is set or has hardened, the resulting slab or flag is removed and when inverted, presents the desired mixed wearing surface on its upper side with the bed situated beneath.

The cross section of the blocks or lengths of rubber employed may be of any other suitable shape. For example it may be of square cross section, see Figure 8, or of T-cross section, see Figure 9, or of wedge cross-section, see Figure 10, or of triangular cross-section, see Figure 11.

In addition to the hereinbefore described wires or rods, other anchoring or connecting means may be provided. For example depending members threaded on some or all of the wires or rods may be arranged to depend into the bed of cement or the like. By way of illustration Figure 12 shows a perforated strip 23 of sheet metal threaded on a wire or rod 24 extending through the rubber block 25, the perforated strip projecting downwards 90 into the bed 26 of cement or the like. Such means may be provided where the wires or rods terminate or in the interstices or apertures or between the adjacent or abutting surfaces of the rubber blocks or rubber blocks 95 and lengths. Another form of anchoring means consists in grooves or flutes provided in the side surfaces of the blocks or lengths of rubber, for example flutes such as indicated by the reference numeral 27 in Figure 8.

Where the wires terminate they may be bent or cranked to project downwards into the bed.

Where the mixed wearing surface is produced in the form of slabs or flags, a border or surrounding edge of cement is preferably 100 provided to enclose the edges of the fabric of rubber and wire.

The said paving can be employed amongst other purposes for paving footpaths, roads, playgrounds, steep slopes, floors of buildings 110 and so forth. Where the paving is intended for roads, the rubber blocks and interstices or apertures are preferably of larger size than when the paving is intended for use by pedestrians only.

While the embodiments of the invention herein particularly described are those now preferred, it is to be understood that in its broad aspects the invention is not confined to the details of the disclosure, which are capable of modification, omission or substitution and are herein recited for explanation and without limitative intent, wherefore all modifications, substitutions, multiplications and omissions, whatsoever, as fall within the scope of the appended claims are to be deemed as included.

I claim—

1. In a pavement, road, tread and the like surface consisting of pieces of soft rubber in-

laid in the upper part of a mass of solid cement during production of the said mass, wires which are threaded through the pieces of rubber and cross over each other inside the pieces of rubber for retaining the pieces of rubber in position in the cement.

2. In a pavement, road, tread and the like surface consisting of pieces of soft rubber inlaid in the upper part of a mass of solid cement during production of the said mass, pieces of rubber having intersecting holes in them, wires threaded through the said holes and crossing each other where the holes intersect and spacing means provided between the said pieces and threaded on the said wires which retain the said pieces in position in the said mass.

3. In a pavement, road, tread and the like surface consisting of pieces of rubber inlaid in the upper part of a mass of solid cement during production of the said mass, oblong pieces of rubber provided with longitudinal holes and cross holes, wires threaded through the longitudinal holes, and wires threaded through the cross holes and crossing the first named wires at one side thereof inside the pieces of rubber.

4. In a pavement, road, tread and the like surface consisting of pieces of rubber inlaid in the upper part of a mass of solid cement during production of the said mass, oblong blocks of soft rubber provided with longitudinal holes extending through them and lateral holes extending through them at the ends, wires on which lateral rows of the said blocks are threaded at spaced distances apart by means of the lateral holes, wires threaded through the said blocks by means of the longitudinal holes and crossing the first named wires inside the blocks and connecting the lateral rows of blocks together and embedded in the said mass between the said rows, the ends of the blocks of one lateral row overlapping the ends of the blocks of the adjacent rows.

5. In a pavement, road, tread and the like surface consisting of pieces of rubber inlaid in the upper part of a mass of solid cement during the production of the said mass, lateral rows of oblong blocks of soft rubber with overlapping ends, lateral wires threaded through lateral holes in the overlapping ends of the blocks and connecting the rows together, longitudinal wires threaded through longitudinal holes in the blocks and crossing the lateral wires inside the blocks, spacing means provided on the lateral wires for retaining the overlapping ends at predetermined distances apart and parts of the mass of cement situated between the blocks and having embedded in them those parts of the wires which are not situated inside the said blocks.

6. In a pavement, road, tread and the like surface consisting of pieces of soft rubber

inlaid in a mass of solid cement during production of the said mass, blocks of rubber having crossing holes through them, and arranged in displaced positions with rows of overlapping ends, wires threaded through and connecting the overlapping ends of each row together, wire coils threaded on the said wires between adjacent overlapping ends and retaining them predetermined distances apart, there being two of the said wires threaded through each block, and other wires threaded through the blocks and crossing the first named wires inside the blocks, the whole forming a selfsustaining rigid fabric and the wires and wire coils being embedded in the said mass between the rubber blocks.

In testimony whereof, I have signed my name to this specification at Manchester, in the county of Lancaster, England, this 13th day of June, 1928.

THOMAS GARE.
